UNITED STATES PATENT OFFICE.

JULIUS ZSOLDOS, OF BROOKLYN, NEW YORK, ASSIGNOR TO AUTOMAT EQUIPMENT CORPORATION, A CORPORATION OF DELAWARE.

COIN-CONTROLLED LIQUID-VENDING MACHINE.

Application filed August 25, 1920. Serial No. 405,920.

This invention relates to liquid vending machines, and is, more particularly, directed to a machine wherein the vending of the liquid is controlled or made dependent upon the introduction of a coin into the machine. Machines for vending liquids, depending upon the insertion of a coin, have been heretofore suggested, but in such machines, it has been the practice to incorporate in the construction a main liquid reservoir, which is adapted, during periods of nonuse, to fill a measuring receptacle, which was adapted to be tilted or otherwise emptied upon the positioning of a coin in the machine and usually through the manual operation of a handle or knob incorporated in the construction.

The object of the present invention is to provide a liquid vending machine, wherein the employment of a measuring receptacle is rendered unnecessary and, accordingly, the period of time required for the filling of such measuring receptacle is eliminated in the present machine. Accordingly, consecutive operations of the machine may take place in rapid succession and immediately after one another without requiring a prospective purchaser to wait a sufficient period to allow of the refilling of the measuring receptacle.

The elimination of the measuring receptacle is accomplished in the present invention through the dispensing of liquid through a time controlled valve of novel and efficient construction and preferably entirely electrically controlled, so that the amount of liquid dispensed is governed entirely by the time which elapses between the opening and closing of the dispensing valve.

Another feature of the invention is the incorporation in a liquid vending machine of novel mechanism adapted to automatically compensate for the difference in hydrostatic pressure in the main reservoir or tank, so that the amount of liquid adapted to be dispensed may at all times be constant through any predetermined period irrespective of the height of column of liquid in the reservoir or tank. By the use of such mechanism, the flow of liquid is so controlled that the amount dispensed when the tank is full will be exactly the same as the amount dispensed when the tank is practically empty.

I preferably associate with the level com-

pensating means, auxiliary mechanism for rendering the flow of liquid steady, for the purpose of obviating pulsations in the flow, and this means is of such simple, highly efficient nature as to, at all times, effect a smooth, even and uniform flow of liquid through the discharge outlet of the machine.

In carrying out the present invention, other novel and efficient means and mechanism are employed, among which may be mentioned improved motor operated cam means for controlling the elapsed time of the dispensing operation, through the manipulation of switches electrically connected with the dispensing valve and this motor operated cam means is, in turn, controlled by further electrical means adapted to render the cam controlled means operative or inoperative depending upon the introduction of a coin into the machine.

Features of the invention, other than those adverted to will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a diagrammatic view of the apparatus of this invention.

Figure 2 is a section on the line 2—2 of Figure 1.

Figure 3 is a front elevation of the motor control and motor controlled mechanism shown in Figure 1.

Figure 4 is a plan view of the mechanism shown in Figure 3.

Figure 5 is a sectional view illustrating the liquid controlling means.

Figure 6 is a perspective detail of the means for precluding the insertion of a coin into the machine until the machine finishes a previous operation.

Figure 7 is a detail perspective of cam mechanism employed; and,

Figure 8 is a detail fragmental view of detent mechanism which is preferably used.

The mechanism of the present invention is, in practice, housed within a suitable casing, but, in the interest of clearness, the casing and other unimportant details have been omitted and the showing in the draw-

ings has been restricted purely to the showing of the essential features of the invention.

The liquid to be dispensed is contained within a suitable reservoir 10, which is in constant communication through a pipe 11, with a supplemental reservoir 12, and the liquid in the reservoir 10 flows unobstructedly into the supplemental reservoir 12, and rises to the same level as in the main reservoir.

The supplemental reservoir 12 has an outlet 13, which communicates with a pipe 14, leading to a valve chamber 15, and this latter chamber has communication through a port 16, with a draw off or discharge pipe 17 leading to the exterior of the casing of the machine, and beneath the open outer end of which a cup, tumbler or other container may be held to receive the liquid dispensed from the machine.

The flow of liquid through the valve port 16 is controlled by a valve 18, the stem of which extends upwardly and is secured to the core of a solenoid 19. A spring 20 is coiled around the valve stem and serves to normally elevate the core of the solenoid and seat the valve 18 to preclude the outflow of the liquid.

Associated with the solenoid core 19 is a solenoid 21, which is connected by a wire 22 to a suitable source of electrical energy 23, and leads back to said source by way of a wire 24, passing through a switch 25, as clearly shown in Figure 1. When the switch 25 is closed, the circuit is completed at this point, the solenoid 21 energized and its core 19 depressed against the tension of the spring 20, for the purpose of unseating the valve 18 and allowing liquid to flow from the outlet pipe 17. In the form of the invention shown, the switch 25 embodies two contacts 26 and 27, the former of which is fixed and the latter of which is movable. The contact 27 is mounted on a leaf spring 28, the tension of which normally carries the contact 27 away from the contact 26, and breaks the circuit through the wire 24 at this point. The switch 25 may be closed, however, by forcing the contact 27 against the contact 26 and this is accomplished, as illustrated, by means of the cam arrangement shown best in Figure 7, which cam arrangement is adapted to cooperate with a nose 29 mounted on the leaf spring 28.

The cam arrangement shown in detail in Figure 7 is shown in connection with other details, in section, in Figure 2, and in plan view of Figure 4. It embodies a cam plate 30 and a cam ring 31. The cam plate 30 is provided around its outer periphery and on its forward face with a channel and in this channel is seated the cam ring 31. The cam plate and cam ring 30 and 31, each are provided on their outer circumference with

raised portions 30' and 31', which form cam tracks preferably swung on substantially the same radius, whereby when the two parts are assembled as shown in Figure 7, the cam track 31' forms a continuation of the cam track 30'. The cam ring 31 is, however, mounted for circumferential adjustment on the plate 30, so that through said circumferential adjustment, the aggregate length of the cam tracks 30 and 31' may be regulated and adjusted as desired and thereafter locked against further relative movement by means of screws 32 after the manner shown in Figures 2 and 7. The cams 30 and 31 are mounted for cooperation with the nose 29 of the switch mechanism 25, and when the cams are revolved at a constant speed, while in engagement with the nose of the switch, the adjustment between the cam plate 30 and the cam ring 31 will, manifestly, control the time during which the switch 25 is closed and will consequently govern the period during which the valve 18 is maintained open through the electrical connections specified.

The cam mechanism shown in Figure 7 is mounted for operation on a stub shaft 33, which is connected through a suitable transmission mechanism 34 to a drive shaft 35, on which is fixed a worm wheel 36 (see Fig. 4). With the worm wheel 36 cooperates a worm 37 mounted on an armature shaft 38 of a motor 40. The cam plate 30 is frictionally supported on the stub shaft 33, as is also a detent disk 41, through the employment of a frictional clutch best shown in Figure 2. This clutch embodies a disk 42 secured to the shaft 33. The detent disk 41, which is loose on the shaft, rests against the disk 42, and a second disk 43 is positioned between the disks 41 and the plate 30. Against the opposite side of the plate 30 rests a felt or fibre disk 44 and against this disk rests a metallic disk 45. The free end of the stub shaft 33 is provided with a nut or screw 46 adapted to retain a washer 47, and a spring 48 is coiled about the shaft between the disk 45 and the washer 47. These parts constitute, in effect, a friction disk clutch which permits of the frictional drive of the detent disk 41 and the cam plate 30 in an efficient although not a positive manner.

Associated with the detent disk 41 is a detent or latch 49 which is maintained in engagement with the disk 48 by means of a leaf spring 50. This leaf spring 50 presses against a bar of insulation 51, which is secured to the latch at 52. The nose of the latch is adapted, when the disk 41 is in proper position, to enter a notch 53 in the periphery of the detent disk 41, which notch is best shown in Figure 8. Within the notch is pivoted a stop plate 54 on the pivot 55 and this stop plate is normally forced into the dotted line position of Figure 8 by means of a spring 56 to maintain the limiting stop 57

in engagement with the wall of the notch. In the normal position of the parts, the detent 49 serves to lock the detent disk 41 against rotation, since at this time the nose of the detent occupies the notch 53 and the parts assume the position shown in full lines in Figure 8. In order to rotate the cam plate 30, and close the switch 25, it is manifestly necessary to withdraw the detent from the position shown in full lines of Figure 8 and at the same time start the motor 40 to rotate the cam surfaces 30' and 31' into engagement with the nose of the spring mechanism 25. This is accomplished in the manner next to be described.

The latch or detent 49 constitutes the armature of an electromagnet 58, included in a circuit 66, which also includes a coin controlled switch 67, and when this switch 67 is closed and the magnet 58 energized, the latch 49 is attracted with the result that its end is withdrawn from the notch 53 of the detent disk while the bar of insulation 51, which it carries, closes the switch 60. The switch 60 embodies two contacts 61 and 62 which are included in a circuit 59, which also includes the motor 40 and the switch 60, as shown in Figure 1. One contact 61 of the switch 60 is mounted on the leaf spring 50, while the other contact 62 is mounted on a second leaf spring 63, supported on a bracket 64. The gap between the contacts 61 and 62 may be regulated by a bolt 65, as shown in Figure 3.

The coin controlled switch 67 shown at the upper portion of Figure 1, embodies two contacts 68 and 69, the former of which is relatively stationary and the latter of which is carried on one arm of a balance 70 pivoted at 71. The balance 70 is provided at one end with a coin receiving member 72 and has a counterbalancing weight 73 at its other end. A coin X inserted in the machine is adapted to traverse a coin chute 74, and fall upon the tray 72. The weight of the coin is sufficient to normally tilt the balance, but said balance is normally maintained in horizontal position by a catch 75 carried by the stem 76 of a push button 77. The catch 75 holds the balance against tilting until the push button 77 is pressed, whereupon the balance tilts, completes the circuit 66 at the switch 67 and thereafter the coin rolls off of the tray into a suitable receptacle, whereupon the balance reassumes its horizontal position and becomes relocked by the catch 75. The operation of the machine as thus far described may be briefly set forth as follows.

A coin X deposited in the machine falls through the chute 74 on to the tray 72. The operator places a cup or tumbler under the liquid outlet spout 17 of the machine and presses the button 77. This releases the balance and brings the contact 69 into engagement with the contact 68, thereby momen-

tarily completing the circuit 66. Upon the completion of this circuit, the magnet 58 is energized, retracts the detent or latch 49 from the notch 53 of the detent disk and simultaneously closes the switch 60. The motor is now energized, and this function is manifested through the rotation of the stub shaft 33, whereby the detent disk 41 and cam plate 30 are rotated.

In the meantime, the withdrawal of the detent 49 from the notch 53 has allowed the stop plate 54 to drop down to the dotted line position of Figure 8, whereby the reentry of the nose of the detent 49 into the notch 53 is precluded following the momentary energizing of the magnet through the tilting of the coin balance. In other words, the stop plate 54 has locked the detent in a position to close the switch 60 and permit of rotation of the friction disks of which the cams 30 and 31 form a part.

It will of course be apparent that when the coin leaves the tray, the balance returns to normal position and separates the contacts 68 and 69, so that the magnet 58 is deenergized, but inasmuch as the latch 49 is held retracted by the disk 42 and the stop plate 54, the motor circuit will remain energized until the switch 60 is permitted to subsequently open when the ends of the detent enter the notch 53 at the conclusion of the dispensing operation.

Through the operation of the motor, the cams 30 and 31 are rotated, while the nose 29 of the switch 25 follows the surface of said cams. At the very start of the operation, the switch 25 is open, but as soon as the cams commence to rotate, the nose 29 engages with the raised cam track 30' and the switch 25 is closed and remains closed through the subsequent rotation of the cams until the cam track 31' has been traversed.

The closing of the switch 25 energizes the solenoid 21, and depresses its core 19 to open the valve 18 and allow liquid to flow through the outlet pipe 17. The liquid continues to flow as long as the switch 25 is closed, but as soon as it is opened, the solenoid 21 is deenergized and the spring 20 seats the valve 18, shutting off the flow of liquid. The cams continue to revolve until the notch 53 of the detent disk becomes juxtaposed with the detent 49, whereupon the nose of the detent enters the notch and allows the switch 60 to open, thereby deenergizing the motor and suddenly stopping the friction clutch from further rotation. The detent brings the cam disks 30, ring 31 and detent disk 41 to a sudden stop and it is for this reason that these parts are designed to be driven from the motor through the friction clutch. This friction clutch compensates for overtravel of the motor and brakes the same to a state of rest.

It will be noted from Figure 1 that a mag-

net 78 is included in a shunt wire 79 in the motor circuit 59 and the function of this magnet will appear in Figure 6. Its armature is in the form of a finger 80 pivoted at 81 and adapted to cooperate with an aperture 82 in the coin race 74. At such times as a coin is in the machine and the motor operating the magnet 78 attracts its armature and draws its free end into the aperture 82 into such position as to preclude the passage of a subsequent coin into the machine. By this means, the insertion of more than one coin by a subsequent purchaser before a previous purchaser has been properly served is precluded. The finger 80 may, in practice, be normally retracted by a spring or may gravitate into a position to allow of the entry of a coin into the machine.

In a machine, wherein the amount of liquid dispensed is governed by the elapse of time of flow, I have found that in order that the amounts of liquid dispensed may be uniform at all times, it is necessary to incorporate in the construction, means adapted to compensate for the varying hydrostatic pressure due to varying amounts of liquid contained in the reservoir. When the reservoir is full, the hydrostatic pressure therein is considerably greater than when the reservoir is almost empty, so that liquid will flow faster and under greater pressure in the first instance than in the latter instance, with the result that more liquid may be dispensed from a full reservoir within a given period than could be dispensed from an almost empty reservoir within the same time. There is, accordingly, incorporated in the machine of this invention means for automatically compensating for the varying hydrostatic pressure and this means is best shown in Figure 5 of the drawings.

Within the supplemental reservoir 12 is positioned a float 83 through which passes a rod 84. The lower end of the rod 84 has fixed thereto a conical regulating valve 85, which works in the cylindrical liquid outlet 13, while the upper end of the rod is attached to a spring 86, the free end of which is secured to an adjusting screw 87. The spring 86 may be adjusted to compensate for the weight of the float 83 and in this manner render the float more buoyant and sensitive. When the liquid level in the reservoir is high, the conical regulating valve 85 is raised, so as to render the area of the outlet 13 more or less constricted. The "head" of water in the reservoir is sufficient to force the proper quantity of liquid through this constricted passage, but as the liquid level becomes lowered, the pressure becomes correspondingly less and the float 83 lowers the regulating valve 85 to a corresponding distance to proportionally enlarge the outlet. In this manner, the flow of

liquid from the reservoir may be maintained constant and unvarying.

When liquid flows past a valve such as the valve 85 there is a tendency of the valve to bob or "chatter", but this is overcome in the present invention by mounting in the side of the reservoir a magnet 88 adapted to cooperate with an armature 89 mounted on the rod 84. This magnet is shunted into the circuit including the solenoid 21 by wires 90, so that when the solenoid is energized and the valve 18 opened, the magnet 90 is simultaneously energized and the regulating valve steadied through the frictional engagement between the core of the magnet 88 and its armature 89.

The hereinbefore described machine is remarkably simple in construction for the functions it performs, the constituent parts operate in a simple and efficient manner, and all cooperate with one another in the vending of fixed amounts of liquid in an expeditious and economical manner. In practice, the mechanism is housed within a neat and compact casing, which may be conveniently constituted to house the main and supplemental receptacles and the coin mechanism within the upper part thereof, and the motor, cams and cooperating mechanism in the lower portion thereof. This arrangement, of course, may be varied, but is highly practical since it brings the discharge spout at a convenient height from the floor.

Having thus fully described the invention, what I claim as new and desire to secure by Letters Patent is:

1. A liquid vending machine embodying a reservoir, provided with an outlet, and means controlled by the liquid level in the reservoir for automatically regulating the area of the outlet to render the flow of liquid through said outlet uniform irrespective of the differences in hydrostatic pressure due to the receding liquid level in the reservoir as the same recedes when the liquid is drawn off, and means for stabilizing the operation of the liquid flow controlling means.

2. A liquid vending machine embodying a reservoir, provided with an outlet, and float controlled means associated with said outlet for automatically changing the area of said outlet to compensate for the difference in hydrostatic pressure as the liquid level recedes when the liquid is drawn off for the purpose of rendering the flow of said liquid from the outlet uniform, and electrical means for stabilizing the operation of the float controlled means.

3. A liquid vending machine embodying a reservoir, provided with an outlet, a regulating valve associated with said outlet, and means controlled by the liquid level in the reservoir for automatically regulating the size of the outlet through the manipulation

of the regulating valve, whereby the flow of the liquid through the outlet is rendered constant irrespective of the difference in hydrostatic pressure due to the receding 5 level of the liquid in the reservoir, as such liquid is drawn off, and electrical means co-operating with the regulating valve for steadyng the operations of the same.

4. A liquid vending machine embodying 10 a reservoir provided with an outlet, a regulating valve associated with said outlet, a float cooperating with said valve and adapted to automatically regulate the same to effect a uniform flow of liquid through the 15 outlet irrespective of the differences in hydrostatic pressure due to the receding of the level when the liquid is drawn off through the outlet, and electrical means for stabilizing the operation of the float and 20 valve.

5. A liquid vending machine embodying a reservoir, provided with an outlet, a regulating valve associated with said outlet, a float 25 cooperating with the regulating valve and controlled by the liquid level in the reservoir to automatically effect a uniform flow of liquid through the outlet irrespective of the differences in hydrostatic pressure due to the drawing off of liquid through the outlet, and 30 means associated with the float for rendering the same more sensitive to changes in liquid level within the reservoir.

6. A liquid vending machine embodying a reservoir, provided with an outlet, a regulating 35 valve associated with said outlet, a float cooperating with the regulating valve and controlled by the liquid level in the reservoir to automatically effect a uniform flow of liquid through the outlet irrespective of the 40 differences in hydrostatic pressure due to the drawing off of liquid through the outlet, and means associated with the float for rendering the same more sensitive to changes in liquid level within the reservoir, in combination 45 with electrical means for stabilizing the operations of the regulating valve.

7. A liquid vending machine embodying a reservoir, provided with a liquid outlet, means associated with said outlet for automatically effecting the uniform flow of liquid through the outlet irrespective of the hydrostatic pressure within the reservoir, a valve adapted to permit or preclude the flow of liquid through the outlet, and electrically 50 operated devices for simultaneously unseating the valve and steadyng the operation of

the means which renders the flow of liquid uniform.

8. A liquid vending machine embodying a reservoir, provided with a liquid outlet, 60 means associated with said outlet for automatically effecting the uniform flow of liquid through the outlet irrespective of the hydrostatic pressure within the reservoir, an electrically operated valve adapted to permit or preclude the flow of liquid through the outlet, and electrically operated means for stabilizing the operations of the flow controlling 65 means, when the valve is unseated.

9. A liquid vending machine embodying 70 a reservoir provided with an outlet, an electrically operated valve associated with said outlet, means, controlled by a prospective purchaser, for holding the electrically operated valve open for a predetermined period to permit of the dispensing of liquid during such period, and means for rendering the flow of liquid through the outlet uniform, irrespective of the amount of liquid in the 75 reservoir.

10. A liquid vending machine embodying a liquid reservoir provided with an outlet, a normally seated valve for normally precluding the flow of liquid from said reservoir, electromagnetic means for unseating said valve, an electric circuit embodying a switch for energizing the electromagnetic means to unseat the valve and permit the flow of liquid, and means, controlled by an intended purchaser, for effecting the closing 80 of said switch and the maintaining of said switch closed, for predetermined periods, during which the liquid is dispensed.

11. A liquid vending machine embodying a liquid reservoir provided with an outlet, a normally seated valve for normally precluding the flow of liquid from said reservoir, electromagnetic means for unseating said valve, an electric circuit embodying a switch for energizing the electromagnetic means to unseat the valve and permit the flow of liquid, and means, controlled by an intended purchaser, for effecting the closing of said switch and the maintaining of said switch closed, for predetermined periods during 95 which the liquid is dispensed, in combination with means for standardizing the amount or quantity of liquid dispensed from the reservoir during a predetermined period.

In testimony whereof, I have signed my 100 name to this specification.

JULIUS ZSOLDOS.
